WARP STOP EQUIPMENT COMPANY, OF PAWTUCKET, RHODE ISLAND.

WARP STOP MOTION FOR LOOMS.

Application filed December 31, 1923. Serial No. 683,669.

My invention relates to warp stop devices for looms and particularly to the "knock-off" mechanism. Its purpose is to insure that when the warp stop functions, the shuttle shall stop at a particular side of the loom: more especially that, in the case of a loom equipped with an automatic filling "magazine" or "battery," the shuttle shall not stop in the box on the same side of the loom with the "magazine." The reason for this is that the bobbin changing mechanism is devised to operate with the loom working, under full impetus of its acquired momentum. Should a change of bobbins occur coincidently with starting the loom which is ponderous and energy absorbing at starting, the changing action is liable to be weak. In such case the new bobbin may not be fully and properly set in the shuttle, and it may become displaced, causing damage to the cloth or to the loom or both.

In the accompanying drawings, forming a part of this specification, the various figures represent as follows: Fig. 1 a conventional representation of the portion of a loom involved, showing the general relation of the elements of my invention and with the shuttle partially in the box.

Figs. 2-3 and 4 show details.

My invention is applicable to any warp stop device in which a movable "danger" or "finger" or "latch" is caused, thru breaking of a warp thread, to be shifted into the path of a moving "bunter," and by its encounter therewith react directly or indirectly upon the loom control. Loom control, for the purposes of this specification, defines and identifies those instrumentalities whereby the action of the loom is started and stopped in the usual course by the operative.

In my invention that element which immediately encounters the "dagger" is hinged or swivelled so that it can be moved and its position is so controlled by the shuttle thru its "binder" or "swell" and connections to be described hereinafter, that only when the shuttle is in the box from which the bunter position is controlled will the bunter and dagger encounter each other. In short, the warp stop can only act when the shuttle is in the particular box whose binder governs the bunter. As this control is in effect on only one side of the loom, it follows that the warp stop can operate only on alternate picks. The internal resistance of a properly

adjusted loom is such that where a warp stop knock-off is made to work at the time the shuttle is in the box depicted, the loom in stopping will turn over under its momentum far enough to throw the shuttle into the opposite box.

Referring to Fig. 1, the lay 1 carries the box 2 with its "binder" or "swell" 3 which is forced outward from the box 2 by the shuttle 4 when in the box. When the shuttle has left the box 2 the "binder" 3 is released and is returned inwardly toward the box by a spring not shown. These are matters well known to those versed in the art of weaving and familiar with weaving machinery.

On the lay, in suitable bearings 5-5 is mounted a lever 6, the upper arm 7 of which, suitably formed bears against and follows the "binder" 3. The spring 8, attached to the arm 7 of the lever 6 holds the end of the arm 7 to contact with the "binder" 3. The lower arm 9 of the lever 6 takes into an eye 10 of the bunter 11. The bunter 11 is hinged or pivoted on the bunter bracket 12 which in turn is secured to the lay 1. The bunter bracket 12 is formed with a slot 13 in which is a block 14 vertically adjustable in the slot and held to the bracket by the nut 15 (Fig. 2) which fits upon the threaded shank 16 of said block. The bunter is hinged or swivelled to the block 14 by the pin 17. Extending laterally from the bunter 11 is an arm 18 in which is the hole 10 above referred to, which receives the arm 9 of the lever 6. The bunter 11 is thus controlled in position by the "binder" 3 which in turn is controlled by the shuttle—according as the shuttle is in the box or not.

A usual form of loom control is here indicated (Fig. 1). A handle rod 19, extends across the loom below the breast beam 20, carrying a handle at each end, of which one 21 is shown. This handle is engaged by a pin 22 with a lock 23 which in turn is connected with the clutch shifting or kindred device by the rod 24. The spring 25 reacting against an abutment 26 and acting against the collar 27 holds the handle 21 in lock; and when the handle is unlocked, the spring shifts the rod 24 as well as the lock 23, releasing the clutch or whatever driving control is employed and causing the loom to stop. Movement of the loom handle 21 in the direction of the arrow A, unlocks the

handle, permits the spring 25 to act, and stops the loom. The loom control will not be further detailed because it is well known and enters into the present invention as a whole. Further there are other known types of loom control with which my invention is equally available without limitation to that shown and described herein.

Mounted on the handle rod 19 is an arm 16 28 suitably secured as by the set screw 29. At the extremity of this arm is the usual warp stop dagger 30. While my invention is not confined to electrical warp stops, I have preferred to show it in conjunction 15 with such a device. Below the dagger 30 is mounted a magnet 31, the armature of which is connected with the dagger 30 by a wire 32. This magnet forms part of an electrical circuit 33 deriving its current from a source 20 of electrical energy 34 and including a drop wire system 35. When a drop wire falls, closing the electrical circuit, the magnet 31 is energized and raises the dagger 30. With each reciprocation of the lay 1, the bunter 25 11 is moved toward and away from the dagger 30. When the shuttle 4 is not in the box 2, the binder 3 is in its relaxed, inward position, and the bunter 11 is held by the lever 6 in a position such that the extremity 30 of the bunter is held to a path of travel away from the dagger 30, so that whether the latter is raised or lowered no encounter can occur between the bunter and dagger. This condition ensues at every alternate pick 35 because the shuttle is in this box only every other pick.

At every intervening alternate pick the shuttle is in this box, in which case the "binder" 3 is pressed outward and acting 40 thru the lever 6 swings the bunter into the position indicated by Fig. 3, where its extremity travels in a path where it will be encountered by the dagger 30, providing the latter is raised into the path of movement of 45 the bunter. In such event, the dagger will yield to the encounter, turning its lever 28 and the rod 19 in the direction of the arrow A and with them the loom handle 21. This, as above explained, unlocks the handle 21 50 and causes the stopping of the loom. The release occurs as the lay is beating forward, with the shuttle in the box. Carried by its momentum, the lay returns to its back stroke position, and the shuttle is thrown across the 55 loom to the opposite box.

Bearing in mind the variety of loom constructions and multitude of warp stop adaptations prevailing, it is obvious that the invention herein set forth will require in its 60 embodiment diversified construction and arrangement.

Therefore, without limiting myself to the precise construction and arrangement set forth herein, I claim:

65 1. In a stopping device for a loom, the

combination with the loom handle, reciprocating lay and binder carried by the lay, stop motion dagger normally at inactive position, means connecting the stop motion dagger with the loom handle and means 70 to shift the stop motion dagger from inactive position to active position, of a shiftable bunter carried by the lay with its extremity moving at some times in path away from the dagger in any position of the latter, and 75 means thru which the binder acts to shift the bunter into a path of travel where its extremity will encounter the dagger when the latter is in active position.

2. In a stopping device for a loom, the 80 combination with the movable dagger of its warp stop, the loom stopping devices and means connecting said dagger therewith, of a bunter moving toward and from said dagger and with its extremity shiftable to move 85 in different paths of travel and at sometimes away from the dagger and means to shift the bunter so that its extremity shall, at pre-determined times, encounter the dagger when the dagger is in acting position. 90

3. The combination with the loom control, warp stop motion comprising a dagger and means to raise the dagger upon breaking of a warp thread, and connections between the dagger and loom control, of a 95 hinged bunter and means to carry it on a part of the loom moving toward and away from the said dagger, a lever engaging the bunter, and means to control the position of the lever to alternately shift the extremity 100 of the bunter from a path of movement in which it cannot encounter the dagger in any position of the latter, to a path of movement in which it shall encounter the dagger when the latter is raised. 105

4. The combination with the control devices of a loom, warp stop motion comprising a dagger, connections between the said controlling devices and warp stop dagger, the lay, shuttle box and its binder, of a 110 bunter bracket carried by the lay, a shiftable bunter mounted on the bunter bracket and a lever also mounted on the lay, said lever engaging by one of its cams the shiftable bunter and by its other arm, bearing 115 against the binder in the manner and for the purposes described.

5. The combination with the controlling devices of a loom, warp stop motion comprising a dagger, connections between the 120 loom controlling devices and warp stop dagger, the lay, shuttle box, shuttle and binder for said shuttle, of a bunter bracket carried by the lay, a shiftable bunter, mounted on the bracket and a lever also mounted on the 125 lay, engaging by one of its arms the shiftable bunter, and by the other arm bearing upon the binder so that, when the shuttle is in the box pressing the binder outward, it holds the bunter in position to encounter 130

the dagger when the latter is active, and when the shuttle is out of the box, the binder in its released position causes the return of the bunter to a station where it cannot encounter the dagger in any other position of the latter.

6. In a loom, the combination with the shuttle, shuttle box, and warp stop motion of means acted upon by the shuttle on entering the box to permit action of the warp stop motion.

7. In a loom, the combination with the shuttle, shuttle box, and warp stop motion, of means acted upon by the shuttle on leaving the box to prevent action of the warp stop motion.

8. In a loom, the combination with the shuttle box, shuttle and binder therefor, of a warp stop motion and means to control the timing of the warp stop motion thru the shuttle binder.

9. In a warp stop motion, the combination with the loom control and movable dagger to react upon said control to stop the loom, of a bunter movable toward and away from said dagger in a path to encounter it and cause such reaction, means to shift the extremity of the bunter in a path transverse

to the plane which defines the position of the dagger to withdraw the bunter from 30 said path of encounter to time the warp stop action.

10. In a warp stop motion, the combination with the loom control, a warp stop dagger to react upon said loom control, which 35 dagger is normally in nonactive position, and movable in a given plane into active position, and means to move the dagger from nonactive to active position, of a bunter movable both toward and away from 40 said dagger and in a direction transverse to the plane of movement of the dagger and means to move the bunter in such transverse direction to escape encounter with said dagger when in active position. 45

11. In a warp stop motion, the combinations with a dagger movable in one plane and means to move the dagger, of a bunter movable to and from the general position of said dagger and having an additional 50 movement transversely of the plane of movement of said dagger and means to impart such transverse movement of the bunter for the purpose specified.

HUDGER BRUNEAU.
